(57) **CLAIM**

I claim the ornamental design for pivot assembly for folding wing of large agricultural implement, as shown and described.

DESCRIPTION

FIG. 1 is a top, front perspective view of pivot assembly for folding wing of large agricultural implement according to an embodiment of the invention.

FIG. 2 is a bottom, rear perspective view of pivot assembly for folding wing of large agricultural implement according to an embodiment of the invention.

FIG. 3 is a top plan view of the pivot assembly for folding wing of large agricultural implement.

FIG. 4 is a front elevational view of the pivot assembly for folding wing of large agricultural implement.

FIG. 5 is a left elevational view of the pivot assembly for folding wing of large agricultural implement.

FIG. 6 is a right elevational view of the pivot assembly for folding wing of large agricultural implement.

FIG. 7 is a rear elevational view of the pivot assembly for folding wing of large agricultural implement; and,

FIG. 8 is a bottom plan view of the pivot assembly for folding wing of large agricultural implement.

1 Claim, 5 Drawing Sheets
